UNITED STATES PATENT OFFICE.

FRED HIRSH, OF NEW YORK, N. Y.

DESIGN FOR A CLASP.

44,063.

Specification for Design.

Patented May 20, 1913.

Application filed August 1, 1912. Serial No. 712,785. Term of patent 14 years.

To all whom it may concern:

Be it known that I, FRED HIRSH, a citizen of the United States, residing in the city of New York, county and State of New York, have invented a new, original, and ornamental Design for a Clasp, of which the following is a specification, reference being had to the accompanying drawing, forming part thereof.

Figure 1 is a front, and Fig. 2, a side, elevation, showing my new design.

The design relates particularly to the front or face of the clasp, which front is

rounded so as to be substantially circular in outline, and the outer end of the clamping member mounted thereon extends slightly beyond the edge of the front and is curved to harmonize with the curvature thereof.

I claim—

The ornamental design for a clasp, as shown and described.

FRED HIRSH.
